UNITED STATES PATENT OFFICE.

HERMAN F. VOSHARDT, OF CHICAGO, ILLINOIS, ASSIGNOR TO FRIEDELEY-VOSHARDT COMPANY, OF CHICAGO, ILLINOIS, A CORPORATION OF ILLINOIS.

DESIGN FOR A LAMP SHADE AND REFLECTOR.

46,418.

Specification for Design.

Patented Sept. 15, 1914.

Application filed June 5, 1914. Serial No. 843,315. Term of patent 3½ years.

To all whom it may concern:

Be it known that I, HERMAN F. VOSHARDT, a citizen of the United States, residing at Chicago, in the county of Cook and State of Illinois, have invented a new, original, and ornamental Design for Lamp Shades and Reflectors, of which the following is a specification, reference being had to the accompanying drawings, forming a part thereof.

In the drawings:—Figure 1 is a top plan view of a shade embodying this design. Fig. 2 is a side elevation of the same with a part broken away to reveal the interior.

I claim:—

The ornamental design for a lamp shade and reflector as shown.

In testimony whereof I have hereunto set my hand at Chicago, Illinois, this 1st day of June, 1914.

HERMAN F. VOSHARDT.
